E. DE BOGOR

TRAFFIC DANGER SIGNAL

Filed May 10, 1923

Inventor

E. Debogory.

By
J. W. Bryant.
Attorney.

UNITED STATES PATENT OFFICE.

EUGENE DE BOGOR, OF DALLAS, TEXAS.

TRAFFIC DANGER SIGNAL.

Application filed May 10, 1923. Serial No. 637,987.

To all whom it may concern:

Be it known that I, EUGENE DE BOGOR, a citizen of the United States of America, residing at Dallas, in the county of Dallas and State of Texas, have invented certain new and useful Improvements in Traffic Danger Signals, of which the following is a specification.

This invention relates to certain new and useful improvements in traffic danger signals of a type best adapted for being positioned at street crossings or along highways for the purpose of warning drivers that they are approaching danger in the form of curves, schools, hills, intersecting streets, or the like.

An important object of the invention is to provide a danger signal that is operative either during daylight hours or after dark for accomplishing the purpose set forth above.

A further object of the invention is to provide a traffic signal of such a nature that it will, with great certainty, attract the attention of all drivers for warning them of the approach of danger on the streets or highway they are traveling over.

Other objects and advantages of the invention will be apparent during the course of the following description.

30 In the accompanying drawing forming a part of this specification and in which like numerals are employed to designate like parts throughout the same,

Figure 1 is a front elevational view of the signalling device embodying this invention,

Figure 2 is a front elevational view of the device shown in Fig. 1 with the door forming a portion of the front wall of the same in its open position to better enable the 40 contents of the casing to be seen, and

Figure 3 is a vertical sectional view, partly broken away of the signal casing embodying this invention and shown in Figs. 1 and 2.

45 In the drawing, wherein for the purpose of illustration is shown a preferred embodiment of this invention, the numeral 5 designates a post of a standard having an enlarged base 6 suitably connected thereto for the purpose of allowing the device to be secured to a roadbed or sidewalk, the said post being provided at its upper end with a collar 7 that is adapted for being suitably secured to the lower arcuate wall 8 of the signal casing which further

consists of a rear wall 9, side walls 10, a relatively small rigid front wall 11 and a hingedly connected door 12 that forms the substantial portion of the front wall of the casing. This door 12 is suitably connected 60 to one side wall 10 by means of the hinges 13 and is also provided with a clasp or locking element 14 that is adapted for coacting with the locking element 15 carried by the opposite side wall of the casing 10 for the 65 purpose of retaining the said door in its closed locked position.

Suitably secured to the rear wall 9 of the said casing are a pair of spaced brackets 16 and 17 which are adapted for supporting a 70 perpendicular shaft 18 that is suitably journaled in bearing portions of the said bracket. Spaced laterally of the perpendicular shaft 18 is an electric motor 19 which is suitably supported by a bracket member 20 secured 75 to the rear wall 9 of the casing. The armature shaft 21 of this electric motor is provided with a bevel pinion 22 which is constantly in mesh with a bevel gear 23 suitably keyed to substantially the lower end of the 80 perpendicular shaft 18 for the purpose of rotating the said shaft when the said motor is supplied with current by the electric wires 24. Referring particularly to Fig. 3 wherein there is shown a horizontally extending post 85 25 that is rigidly connected, as at 26 to the rear wall 9 of the casing as shown. Loosely mounted upon the perpendicular shaft 18 is a sleeve 27 that is provided with upwardly extending arms 28 having bearing portions 90 29 formed at their extreme outer ends which are adapted for encircling sleeves 30 rotatably mounted upon the horizontal post 25 and provided with beveled gears 31 upon their inner ends. These beveled gears 31 95 are constantly in mesh with a beveled gear 32 suitably keyed to the extreme upper end of the perpendicular shaft 18 and engaging the same on diametrically opposite sides.

The sleeve members 30 are each provided 100 with a pair of oppositely extending radial spokes 33 which are suitably connected at their outer ends to signalling disks A, B, C, and D, as best indicated in Fig. 3. These disks A, B, C, and D are preferably all of 105 different colors such as red, blue, green, and white.

In this showing of the invention, the door 12 is provided with a series of letters 34 that are formed by properly perforating the said 110

door as best shown in Fig. 1. Secured to the inner face of the door 12 are guiding flanges 35 that are adapted for engaging the upper and lower edges of a removable pane 5 of glass 36 which is preferably red. Suitably mounted upon the inner face of the arcuate bottom wall 8 is an electric bulb 36 which is provided with a reflector 37 adapted for throwing the rays of light upwardly 10 to illuminate the disks and the perforated letters carried by the said casing. This electric bulb 36 is supplied with current from the electric wires 24 by branch wires 24^a as best shown in Fig. 2. It is to be understood 15 that this application is not limited to words formed by imperforating the door 12 for the said danger indicating words may be painted upon the front face of the same where-upon an electric bulb 36^a and reflector 37^a 20 may be mounted outwardly of the casing upon the relatively small rigid front wall 10, as shown in dotted lines in Fig. 1. The operation of the device is as follows:

When current is supplied to the electric 25 motor 19, the perpendicular shaft 18 will be rotated due to the gear connection formed with the armature shaft 21. The rotation of the perpendicular shaft 18 will cause the spokes 33 carried by the rotatable sleeves 30 30 to rotate in opposite directions due to the position of the bevel gears 31 on diametrically opposite sides of the bevel gear 33 carried by said perpendicular shaft. This rotation of the sleeves 30 in opposite directions will cause the disks C and D to move 35 on an arcuate path above the upper open end of the casing starting from the left hand side of the same and disappearing within the casing on the right hand side. 40 The two remaining disks A and B will be caused to move through an arcuate path above the said casing in an opposite direction to the movement of the disks C and D appearing from the right hand side of the 45 casing and disappearing at the left hand side of the casing. The passing points of the said disks are intended to occur when the disks C and D are positioned in their 50 full line showing as in Fig. 2. The other two disks A and B being at this time directly in line with the disks C and D or in other words positioned directly rearwardly of the same. The second passing point will occur when the disk C has been moved into 55 the position shown in dotted lines at the left hand side of the casing in Fig. 2. This movement of the disks in opposite directions will tend to indicate that there is but one disk moving on arcuate paths in opposite directions above the casing, the said disk changing in color as it changes the direction of movement from the right to the left or vice versa.

60 It is to be understood that the form of this invention herewith shown and described

is to be taken as the preferred example of the same, and that various changes in the shape, size, and arrangement of parts may be resorted to without departing from the spirit of the invention or the scope of the 70 subjoined claims. Obviously, a weight, spring or other form of motor may be substituted for the electric motor 19, while the discs A, B, C and D may be in the form of lamps or electrically illuminated if desired. 75

Having thus described the invention, I claim:—

1. In a signal apparatus, a casing, a series of signalling members rotatably supported in said casing adapted to travel arcuate paths above the same, and means for causing a portion of said members to travel in one direction while the remaining members are traveling in the opposite direction. 80

2. In a signal apparatus, a casing having 85 an opening, a series of signaling members movably supported in said casing adapted for successively appearing and disappearing from view through said opening, and means for causing such movement of said 90 members.

3. In a signalling apparatus, a casing, a supporting element positioned within said casing, a series of signalling members rotatably carried by said support adapted for travelling arcuate paths above the same, said signalling members being divided into two groups, the members of one group travelling in a direction opposite to that of the other group, and means for rotating said 100 members.

4. In a signalling apparatus, a casing, a supporting element positioned within said casing, a series of signalling members rotatably carried by said support adapted for travelling arcuate paths above said casing, said signalling members being divided into two groups with an even number of members in each group, the members of one group travelling in a direction opposite to that of the other group, and means for rotating said members. 110

5. In a signalling apparatus, a casing, a horizontally extending supporting element rigidly mounted in said casing, two groups of signalling members rotatably carried by said supporting element, each group of members rotating around said support in opposite directions to travel arcuate paths above said casing, and means for operating said signalling members. 120

6. In a signalling apparatus, a casing, a horizontally extending supporting element mounted in said casing in spaced relation to its top, a series of spokes rotatably carried by said supporting element, a signalling member carried by each spoke, the length of said spokes being greater than the distance between said supporting element and top 125 of said casing for causing said spokes to 130

travel arcuate paths above the casing, and means for operating said spokes.

7. In a signalling apparatus, a casing, a horizontally extending supporting element 5 mounted in said casing, a pair of sleeves rotatably mounted upon said supporting element, signalling members rigidly connected with said sleeves, and means for rotating said sleeves in opposite directions for causing said signalling members to travel arcuate paths above said casing.

8. In signalling apparatus, a casing, a horizontally extending supporting element mounted in said casing, sleeves rotatably 15 mounted upon said supporting element, signalling members rigidly connected with said sleeves, a horizontal shaft journaled in said casing, means for connecting said shaft and said sleeves for causing the latter to rotate 20 in opposite directions, and means for rotating said horizontal shaft.

9. In a signal apparatus, a casing, a series 25 of signalling members rotatably supported within said casing adapted to travel arcuate paths in view exteriorly of the latter, said members being divided into two groups with the members of each group traveling in a direction opposite to that of the other group, and means for rotating said members 30 whereby a member of one group will appear

in view as a member of the other group is disappearing from view.

10. In a signal apparatus, a casing, a series of signalling members rotatably supported within said casing adapted to travel 35 arcuate paths exteriorly of the same appearing and disappearing from opposite sides thereof, said members being divided into two groups with the members of one group traveling in a direction opposite to that of the other group, and means for rotating said members 40 so that there will appear to be only one member reversely traveling in an arcuate path exteriorly of said casing.

11. In a signal apparatus, a casing, 45 pairs of signalling members rotatably supported within said casing with each pair adapted to travel an arcuate path exteriorly of the latter in an opposite direction from the remaining pair, the members of one pair 50 being of different color to the members of the other pair, and means for rotating said members so that there will appear to be only one member traveling an arcuate path successively in opposite directions with the 55 color of the member changing with the direction of travel.

In testimony whereof I affix my signature.

EUGENE DE BOGOR.
